UNITED STATES PATENT OFFICE

2,491,869

PISTON ENGINE

Béla Marton and Ernö Reich, Budapest, Hungary

Application March 18, 1947, Serial No. 735,336

7 Claims. (Cl. 123—50)

1

This invention relates to a piston engine the working chamber of which is located in the internal cavity of the piston.

The objects of the invention are:

(1) To create a piston engine, which, when used as an internal combustion engine, will protect the cylinder wall, and, more particularly, the layer of oil adhering to the cylinder wall, against the effects of the flame in the combustion chamber;

(2) To enable, in the case of two-stroke cycle engines, absolutely perfect uni-flow scavenging to be realised by the cavity piston;

(3) To admit very high temperatures in the piston cavity, without jeopardising the lubrication of the piston, thereby assuring easier starting and safe ignition;

(4) To enable, in the case of double-piston engines with pin drive projecting laterally from the cylinder, the piston wall to be made so thin as to cause it to yield to the internal pressure and thus to result, in the case of a ground-in piston, in better tightness against leakage than obtainable by means of piston rings;

(5) To enable connecting-rods to be dispensed with and side pressures of the pistons to be reduced;

(6) To enable, in the case of a double-cavity piston, any desired kind of two-stroke cycle diagram to be obtained by employing suitable control in the case of piston steam engines, compressors, pumps, compressed-air engines, etc.;

(7) To enable cross-sections of relatively great magnitude to be opened and closed in the vicinity of the dead-centre points, with a minimum of throttling;

(8) To enable high speeds to be obtainable in all fields of application of piston engines, and smooth running to be assured at high speeds also owing to the small masses of the thin-walled piston;

(9) To enable, in case the driving engine is direct-coupled with a motor or generator, etc., the shaft and journalling devices of the coupled apparatus to be constructed so as to constitute, at the same time, the shaft and bearings of the piston engine, thereby rendering the design simpler and less expensive owing to saving a shaft, its journalling devices and a connecting-rod.

The invention consists, substantially, in the working chamber being situated in the internal cavity of the piston, and the driving pin of the latter being located outside the piston cavity and joining on to the piston bottom.

2

In the case of double-acting piston engines, two hollow pistons, the bottoms of which face each other, or one double piston comprising a common bottom, are slideable inside a cylinder. The piston drive is performed by means of a driving pin located outside the cavity, the said driving pin being fixed between the two pistons, or at their bottom, and its extension piece projecting sideways from the cylinder oscillating in a plane perpendicular on the piston axis, and following the motion of the reciprocating piston. Accordingly, the double-acting cavity piston will, in addition to its alternating motion following the sine law, also perform an oscillating motion around its longitudinal axis. This will enable the inlet and outlet ports cut into the piston and into the cylinder wall respectively to be controlled not only in the vicinity of the dead-centre point, but at all points of the stroke.

The annexed drawing illustrates a number of embodiments, shown by way of example, of the invention.

Fig. 1 is a longitudinal sectional view of a horizontally-arranged double-piston engine in its application as a compressor, air engine, or steam engine for individual drive, in the left dead-centre position.

Fig. 2 is a sectional view on line II—II of Fig. 1 in the middle position of the driving pin.

Fig. 3 is a diagrammatic view illustrating a control port for compressors.

Fig. 4 is a cross-section of another embodiment of a double-piston engine in its application as a steam engine.

Fig. 5 is a diagrammatic view of the control port rendering possible the control of the degree of admission of steam.

In the case of the engine shown on Fig. 1 a double-acting hollow piston 1, or two such pistons possessing a common bottom are fitted into the cylinder 6. The open ends of the cavities of the pistons are closed by tapered extension pieces 12 of the cylinder covers 7 projecting into the piston cavities. In the common bottom 13 of the pistons 1 there is fixed a driving pin 2 projecting sideways, and constructed as a driving arm, which ends in a sphere 8. The latter projects into an eccentrically-situated borehole 9 of the crank disc 10. When the crank disc 10 is being rotated, the

double hollow piston 1 will, by means of the driving arm 2, receive, in addition to an alternating motion, also, at the same time, an oscillating motion, as the driving arm 2 oscillates in a plane perpendicular on the longitudinal piston axis and partaking in the alternating motion of the piston,

If, by means of a drawing needle introduced into the inlet or outlet openings *a* of the cylinder *6*, the motion of the hollow piston is traced on the envelope of the latter, this will give a space curve, resembling an ellipse, as shown in staggered lines on Fig. 3.

If the wall of the double piston is perforated at four places—two of which are situated on one, and two on the other side of the piston bottom—in lengths suitable for purposes of control, along the length of the curves resembling an ellipse as per Fig. 3, control slots *15* will be obtained in the piston wall, which control slots will come into cover with the holes *a* and will, during the length of time, during which such control lasts, communicate with the said holes along a predetermined length of stroke, and will thereby control inlet and outlet. In Fig. 3 the control slot *15* of a compressor is situated in the dead-centre position; in the position *15'* it is in cover with the opening *a*, thereby enabling the compressed air to be exhausted. By suitably choosing the length and width of the slot *15*, it is possible to ensure that in the piston cavities the desired cycle of work suction, compression, exhaust should be performed.

The control slots may, instead of perforating the wall of the hollow piston, be recessed into the cylinder wall as ducts or hole rows *c* (Fig. 5). On the piston wall, one or more boreholes *b* will be provided. In the wall of the cylinder *6* a row of ducts or holes *c* leading to the casing *23* of slide *22* is arranged (Fig. 4). In order to control the machine the slides *22* are rotatably or shiftably arranged for opening or shutting some holes *c*. The pressure is admitted at *25*. The opened holes are marked black while the shut holes are left white. The discharge is carried out through channel *24*. This will enable to control, for instance, the degree of admission, and reversing, in the case of steam engines, or to control the starting of the engine by means of compressed air.

In the case of direct drives, the cylinder *6* is fixed on a flange *17* of the bearing shield *18*, the crank disc *10* being fixed on the axle journal *19* of the axle *20*, running in the bearing *21*, of the machine direct-coupled with the piston engine. Thereby, the provision of a driving axle for the piston engine and of journalling devices for such axle, will be rendered unnecessary.

It is an embodiment of this kind that is shown on Fig. 1 and Fig. 2.

In Fig. 4, the sphere *8* is not directly supported on the wall of the recess *9* of the crank disc *10*, but is supported in rings *15, 16* mounted into the said disc, so as to enable greater pressures to be transmitted by the sphere *8* to the crank disc *10*. The control ports *c* are recessed into bulges of the cylinder wall *6*. The perforations of the double piston are in this case constructed as holes *b*, and the openings *a* are communicating with the row of holes *c* (Fig. 5).

In its constructional details the apparatus according to the invention may be varied in many ways, without departing from the scope of the invention.

What we claim is:

1. A double acting piston engine comprising a cylinder, two hollow pistons arranged with their bottom facing each other in said cylinder, heads on the ends of the cylinder, extension pieces carried by said heads and closing the cavities in the pistons, a single driving pin rigidly fixed at one

end between the two pistons and having its other end protruding from the side of the cylinder, a crank disc having a socket eccentrically mounted therein, and a ball carried by the end of the pin and mounted in said socket.

2. A double acting piston engine comprising a cylinder, two hollow pistons arranged with their bottom facing each other in said cylinder, heads on the ends of the cylinder, extension pieces carried by said heads and closing the cavities in the pistons, a single driving pin rigidly fixed at one end between the two pistons and having its other end protruding from the side of the cylinder, a crank disc having a socket eccentrically mounted therein, and a ball carried by the end of the pin and mounted in said socket, said driving pin which oscillates together with the pistons in a plane perpendicular to the piston axis and follows the reciprocating motion of the pistons.

3. A double acting piston engine comprising a cylinder, two hollow pistons arranged with their bottom facing each other in said cylinder, heads on the ends of the cylinder, extension pieces carried by said heads and closing the cavities in the pistons, a single driving pin rigidly fixed at one end between the two pistons and having its other end protruding from the side of the cylinder, a crank disc having a socket eccentrically mounted therein, a sphere having a bore extending therethrough slidably mounted on the outer end of the pin, a pair of rings having spherical seats formed thereon, mounted in said socket and cooperating with said sphere for transmitting motion between the crank pin and the disc.

35. 4. A double acting piston engine as claimed in claim 1 having control slots recessed into the cylinder wall in the form of rows of holes cooperating with bore holes of the hollow pistons.

5. A double acting piston engine as claimed in 40 claim 1 having control slots recessed into the cylinder wall in the form of rows of holes cooperating with bore holes of the hollow pistons, some of the holes being open and slides closing others of them.

45. 6. A double acting piston engine as claimed in claim 1 wherein the crank disc of the piston engine is directly fixed on the axle of a machine operated by the piston engine thus constituting a direct couple between them, whereby they have 50 common bearings.

7. A double acting piston engine as claimed in claim 1 wherein the crank disc of the piston engine is directly fixed on the axle of a machine operating the piston engine thus constituting a direct couple between them, whereby they have common bearings.
